Term of patent 14 years

Int. Cl. D12—16

U.S. Cl. D14—6

FIG. 1 is a top plan view of my foot platform for trucks showing my new design;

FIG. 2 is a bottom plan view thereof;

FIG. 3 is a side elevational view taken along the right side in FIG. 1, the opposite side being a mirror image thereof;

FIG. 4 is an end elevational view, the opposite end being a mirror image thereof;

FIG. 5 is a cross-sectional view taken along line 5—5 in FIG. 1;

FIG. 6 is a cross-sectional view taken along line 6—6 in FIG. 1;

FIG. 7 is an enlarged fragmentary top plan view of the top left-hand corner in FIG. 1;

FIG. 8 is a cross-sectional view taken along line 8—8 in FIG. 7; and

FIG. 9 is a cross-sectional view taken along line 9—9 in FIG. 7.

It is to be understood that the perforated material is

fragmentarily shown in FIGS. 1 and 2 for convenience of illustration only.

I claim:

The ornamental design for a foot platform for trucks, substantially as shown and described.
